HYDRAULIC PUMP JACK FOR WELLS

Richard D. Hill, Fort Worth, Tex., assignor of one-half to J. R. Dulaney, one-eighth to Fieldon Dulaney, one-eighth to L. C. Dulaney, all of Ardmore, Okla., and one-fourth to O. J. Anderson, Iowa Park, Tex.

Application December 15, 1932, Serial No. 647,342

13 Claims. (CL 103—45)

This invention relates to new and useful improvements in hydraulic pump jacks for wells.

One object of the invention is to provide an improved hydraulic pump jack, which may be conveniently and readily arranged at a well to transmit motion from the pull rod of a pumping power to the pump rods in the well, whereby the well is pumped.

Another object of the invention is to provide a hydraulic pump jack of a simple, economical and durable construction, as well as one which will be compact and free from superfluous and obtrusive parts, thus making for easy installation and a clean-cut apparatus requiring a minimum maintenance.

A particular object of the invention is to eliminate the stuffing box as well as the polish rod, which are usually employed at the top of the well, which cause wear and are a constant source of repair and trouble, as well as increasing the frictional load.

Still another object of the invention is to provide an elongated vertical housing or casing arranged to be mounted axially above the well pipe and having therein a piston cylinder so arranged as to contain the actuating liquid free from contact with any oil or gas which might flow into the housing from the well pipe, even though such oil reaches a considerable height in said housing.

A further object of the invention is to provide a hydraulic jack including elements so constructed and arranged that the loss or dissipation of the hydraulic fluid will be negligible and only infrequent replenishing will be necessary.

A construction designed to carry out the invention will be hereinafter described, together with other features of the invention.

The invention will be more readily understood from a reading of the following specification and by reference to the accompanying drawings in which an example of the invention is shown, and wherein:

Figure 1 is a perspective view of a pump jack constructed in accordance with the invention and mounted on a well.

Figure 2 is an enlarged vertical sectional view of the upper portion of the pump rod lifting structure.

Figure 3 is a vertical sectional view of the lower portion thereof.

Figure 4 is a vertical sectional view taken on the line 4—4 of Figure 2.

Figure 5 is a horizontal cross-sectional view taken on the line 5—5 of Figure 4.

Figure 6 is a horizontal cross-sectional view taken on the line 6—6 of Figure 4, the pipe being shown in plan.

Figure 7 is a view of the power member of the jack, portions being shown in plan and portions in longitudinal section.

Figure 8 is a side elevation of the same, and Figure 9 is an enlarged horizontal cross-sectional view taken on the line 9—9 of Figure 7.

This application is filed as a continuation in part of my former application filed June 16, 1932, Serial No. 617,519, now abandoned.

In the drawings the numeral 10 designates an elongated upright cylindrical casing or housing forming part of the rod lifting member of the jack. The upper end of the housing is provided with a cap 11 having an eye 12 for receiving a hoist connection when it is desired to lift or support the cylinder. The lower end of the housing is supported in a cap 13 having a reduced screw-threaded nipple 14, which latter is screwed into a union 15. The union is screwed onto a nipple 16 mounted in a T connection 17, which in turn is secured in the top of the casing head 18, which latter is mounted on the well casing in the usual manner.

By this arrangement the housing 10 is rigidly supported in an upright position. It is pointed out that not only is the usual stuffing box eliminated, but the polish rod now in common use is absolutely dispensed with and all of the maintenance, wear and trouble resulting from the use of stuffing boxes and polish rods are overcome. Whenever it is desired to disconnect the housing 10, it is merely necessary to unfasten the union 15 and lift the housing by its eye 12.

The housing is split at its center portion and the upper and lower members are screwed into a coupling collar 19, which is shown in detail in Figure 4. This coupling has a transverse web 20, which is provided with a radial hollow boss 21 and an axial integral collar 22 on its upper side. The collar and the boss communicate and a fluid conducting pipe 23 is screwed into the outer end of the boss. A reduced piston cylinder 24 (Figures 2 and 4) has its lower end screwed into the collar 22, while its upper end is open. A piston rod 25 extends down into the cylinder and carries a piston head 26 made up of a plurality of inverted flexible cups 27.

A crosshead 28 is fastened on the upper end of the piston rod and bridle rods 29 extend downwardly on each side of the cylinder. These rods pass through guides 30 in the web 20 and are connected at their lower ends to a lower cross-

head 31. A stub rod 32 has its upper end secured in the crosshead and is disposed substantially axially of the housing 10. The rod 32 has a coupling socket 33 on its lower end so that the pin 5 of an ordinary sucker rod 34 may be screwed thereto. The rod extends down through the housing and loosely through the parts 13 to 18 inclusive, into the well casing in the usual manner.

10 It will be seen that when a fluid, such as oil, is forced into the cylinder 24, the piston 26 will be elevated, thus lifting the pump rod 34. A discharge pipe 35, as shown in Figure 1, extends from the T connection 17 so that the oil which is 80 lifted by the pump (not shown) will be discharged through this pipe. Surplus oil may flow up into the lower section of the housing 10 and it is improbable that it would ever reach the web 20, but even if it did, it would not interfere with the operation of the jack.

15 The actuating member of the jack includes a horizontal cylinder 36, which is shown in detail in Figures 7, 8 and 9. The cylinder is provided at one end with a head 37 having an integral 85 elbow 38. An upright pipe 39 has its lower end screwed into the elbow, while its upper end is connected to the pipe 23 by an elbow 40. A suitable injection valve 41 is connected in the pipe 39, and when necessary additional liquid may be forced into the line through this valve.

20 The cylinder 36 has a collar 42 on its rear end and this end may be open, thus doing away with a stuffing box. A yoke 43 has its ends secured in ears 44 integral with the collar 42 and this yoke 25 is engaged with a hook 45 inserted in a post 46 secured in the ground, or otherwise rigidly supported. By this arrangement the cylinder 36 is anchored and said cylinder may also rest upon any suitable support, as a block 47.

25 A piston rod 48 enters the open end of the cylinder and has thereon a piston head 49, including a plurality of flexible cups 50 similar to the piston 26. These cups are disposed with their open sides toward the oil in the cylinder, which is 30 located between the piston and the head 37. It is important to maintain a solid body of oil between the pistons 26 and 49. Oil being substantially non-compressible, it is obvious that when one piston is moved the displacement of the oil 35 will cause the other piston to be likewise moved. The invention is not to be limited to the use of oil as any other liquid or fluid suitable for the purpose may be employed.

40 On the outer end of the piston 48, I fasten a crosshead 51, which is connected with a crosshead 52 by bridle rods 53 passing through guides 54 on the collar 42 and similar guides 55 on the head 37. The crosshead 52 carries an eye 56 for receiving the hook 57 of the pumping power pull rod 58.

45 The operation is as follows:

50 When the pumping power (not shown) pulls the rod 58, the reciprocating member or carriage, formed by the heads 51 and 52 and the rods 53, is slid forwardly, whereby the piston 59 is moved inwardly or forwardly in the cylinder 36 by means of the piston rod 48. This forward movement of the piston 49 displaces the oil from the cylinder 36 and imparts motion to the oil standing in the pipes 39 and 23 and the cylinder 24 in the housing 10. As the forward movement of the piston 49 continues, the movement of the oil is likewise continued, whereby the piston 26 is moved upwardly or elevated in the cylinder 24.

55 The lifting action which has been described

elevates the carriage or lifting member formed by the heads 28 and 31 and the rods 29, whereby the pump rod 34 is elevated or lifted. When the pump rod 34 is lifted, the pump (not shown) down in the well is operated and the oil or water in the well is thus lifted. The lifted oil flows out through the pipe 35 in the usual manner. It will be seen that a long stroke or lift of the pump rod may be obtained and this is controlled by the length of the cylinders 24 and 36, as well as the travel of the rod 58. The relative diameters of the cylinders 24 and 36 would also control the stroke, by controlling the displacement of the liquid from one to the other.

60 When the pull on the rod 58 is relieved, the weight of the pump rod 34, which extends the length of the well, will cause it to drop, thus pulling the piston 26 downwardly by reason of the crosshead and bridle rod connections. This will displace the oil in the cylinder 24 and impart a reverse movement to the oil in the pipes 23 and 39 and the cylinder 36, whereby the piston 49 will be driven rearwardly to its position for starting another cycle of operation.

65 When the piston 49 is moved rearwardly, the pull rod 48 will be likewise moved by the crosshead and bridle rod connections, thus taking up the slack in the rod. The oil in travelling from the cylinder 24 through the pipes 23 and 39 will be somewhat retarded in its flow, and, therefore, 105 the descent of the piston 26 will be gradual rather than sudden. This will cushion the down stroke of the pump rods and save them from injury, as well as providing a more even and regular operation.

70 While I have shown the housing 10 as an enclosed cylinder, the invention is not to be limited to such, as any support suitable for the purpose and adapted to receive liquid at its lower end could be used. Also any hydraulic means for actuating the piston 26 could be employed so long as liquid was introduced into the cylinder 24 to elevate the piston and exhausted therefrom to lower said piston. The nipple 14 and the connections 15, 16, 17 and 18, or the like, are important as they are large enough to permit the free upward passage of the pump rod 24 as well as surplus liquid, thereby eliminating a stuffing box and the usual polish rod.

75 The description which has been given, recites 125 more or less detail of a particular embodiment of the invention, which is set forth as new and useful, however, I desire it understood that the invention is not limited to such exact details of construction, because it is manifest that changes 130 and modifications may be made, within the scope of the appended claims, without departing from the spirit of the invention.

80 What I claim and desire to secure by Letters Patent, is:

1. In a hydraulic jack, an enclosed upright housing mounted on the upper end of a well and connected to the well tubing, the tubing and housing being in open communication, a cylinder mounted in the housing, a piston reciprocating 140 in the cylinder, a piston rod extending from the piston, means for connecting the piston rod with the pump rods of the well, an actuating cylinder, a piston operating in the actuating cylinder, a liquid conductor between the cylinders, means for 145 sustaining the actuating cylinder, and a pull rod connection connected with the piston of the actuating cylinder.

2. In a hydraulic jack, an enclosed upright housing, a cylinder supported in the housing, a 150

- piston working in said cylinder, a rod carriage connected with said piston, an actuating cylinder, a liquid conductor connecting said cylinders, a piston working in the actuating cylinder, and a pull rod connection attached to said piston. 80
3. In a hydraulic jack, an enclosed upright housing having a well connection at its lower end, a cylinder mounted in the housing, a rod carriage mounted to reciprocate in the housing, a piston mounted in the cylinder and connected with the rod carriage, and hydraulic actuating means disposed exteriorly of the housing and connected with the cylinder for actuating the piston therein. 85
16. 4. In a hydraulic jack, an enclosed upright housing having a well connection at its lower end, a cylinder mounted in the housing, a rod carriage mounted to reciprocate in the housing, a piston mounted in the cylinder and connected with the rod carriage, an actuating cylinder, a liquid conductor between the actuating cylinder and the cylinder in the housing, a piston working in the actuating cylinder, and a carriage connected with the actuating piston and having means for connecting with a pumping power pull rod. 90
33. 5. In a hydraulic jack, an enclosed upright housing having a connection at its lower end for mounting on a well and loosely receiving the pump rod, hydraulic means within the cylinder for connection with the pump rod arranged to elevate said rod and to cushion the down stroke thereof, and hydraulic actuating means mounted exteriorly of the housing and connected with the hydraulic means thereof. 95
33. 6. In a hydraulic jack, an upright housing for containing a liquid at its lower portion, a connection at the bottom of the housing for mounting it on a well and open for admitting liquid to the housing, a cylinder disposed vertically in the housing and having its upper end open, a piston disposed in the cylinder, a piston rod extending from the piston upwardly through the open end of the cylinder, a rod carriage mounted to reciprocate in the housing and connected with the piston rod, a liquid conductor connected with the lower end of the cylinder and means for forcing a liquid through the conductor to the cylinder and for draining said liquid from said cylinder. 100
40. 7. In a hydraulic jack, an enclosed upright housing for mounting on a well, a support in the housing at the midportion thereof, a vertical cylinder in the upper portion of the housing carried by said support, a piston working in the cylinder, a rod carriage mounted to reciprocate in the housing and connected with the piston, a liquid conductor connected with the lower end of the cylinder, an actuator for forcing liquid through said conductor and for permitting liquid to drain through said conductor, and means for connecting said actuator with a pumping power pull rod. 105
45. 8. In a hydraulic jack, an upright cylindrical housing, a cap secured on the lower end of the housing and provided with a reduced nipple, means for connecting the nipple with the tubing of a well for providing an unobstructed overflow of the liquid into the lower end of the housing, the nipple and connections being of such size as to permit a free and unrestricted upward passage of the pump rod into the housing, an upright cylinder mounted in the housing, a piston
- working in the cylinder, a carriage connected with the piston, means for connecting the carriage with a pump rod within the housing, a pipe connection extending from the cylinder outwardly through the housing, and a hydraulic actuator connected with the pipe connection for actuating the piston. 110
9. In a hydraulic jack, an upright cylindrical housing including upper and lower sections and a collar receiving said sections, a transverse support in the collar between the sections, a cylinder carried by the support and extending upwardly in the upper section of the housing, a pipe entering the collar and communicating with the cylinder through said support, a piston mounted in the cylinder, a piston rod extending upwardly from the piston and projecting from the cylinder, a cross head carried by the piston rod, bridle rods depending from the crosshead through the support of the collar and into the lower section of the housing, a bottom crosshead connected to the bridle rods, a stub carried by the bottom crosshead having means for attaching to a pump rod, and a hydraulic actuator connected with the pipe. 115
10. In a hydraulic jack, an enclosed upright housing having a connection at its lower end for mounting on a well and loosely receiving a pump rod, an upright cylinder mounted in the housing, an elongated piston working in the cylinder and including a plurality of longitudinally spaced packing elements engaging the wall of the cylinder, a piston rod extending from the piston and also extending from the cylinder within the housing, a rod carrier mounted in the housing and connected with the piston rod, and hydraulic actuating means connected with the cylinder. 120
11. In a hydraulic jack, a coupling collar having a transverse web and internally screw-threaded on each side of the web, the web having a liquid passage therethrough, an upright cylinder having its lower end mounted in the web and open to the passage thereof, housing sections screwed into the opposite ends of the collar, a piston mounted in the cylinder, a rod carrier slideable through the web and connected with the piston, and means for supplying a liquid under pressure to the passage of the web. 125
12. In a hydraulic jack, an upright support rigidly mounted on the upper end of a well and open to receive liquid from the well, an upright cylinder carried by the support, a piston working in said cylinder, a rod carrier in the support connected with the piston and having means for attaching to a pump rod extending from the well into the support, and means for supplying and withdrawing a liquid from the cylinder to operate the piston. 130
13. In a hydraulic jack, an upright support rigidly mounted on the upper end of a well and open to receive liquid from the well, an upright cylinder carried by the support, a piston working in said cylinder, a rod carrier in the support connected with the piston and having means for attaching to a pump rod extending from the well into the support, a hydraulic cylinder, a piston working in the hydraulic cylinder, a liquid conductor connecting the cylinders for conveying liquid from one cylinder to the other cylinder between their pistons, and means for connecting the piston of the hydraulic cylinder with a pumping power pull rod. 135

RICHARD D. HILL.
